I. Van Olinda

UNITED STATES PATENT OFFICE.

ISAAC VAN OLINDA, OF BROOKLYN, NEW YORK.

IMPROVEMENT IN COMMUNICATING RECIPROCATING MOTION TO PUMPS, &c.

Specification forming part of Letters Patent No. 58,918, dated October 16, 1866; antedated October 5, 1866.

To all whom it may concern:

Be it known that I, ISAAC VAN OLINDA, of the city, county, and State of New York, have invented a new and Improved Method of Communicating Reciprocating Motion to Pump-Pistons, &c.; and I do hereby declare that the following is a full, clear, and exact description of the same, reference being had to the annexed drawings, making a part of this specification, in which—

Figure 1 is a side elevation. Fig. 2 is a horizontal transverse section taken in the line $x x$ of Fig. 1.

Similar letters of reference indicate corresponding parts in both figures.

This invention relates to that class of pumps in which the piston-rod is made hollow, to serve as the discharge-pipe when the pump is in operation; and it consists in a novel arrangement of parts for working the said piston-rod, by which it is caused to reciprocate in a straight line instead of being bent or turned aside during its stroke by the arc described by the end of the operating-lever with which it is connected.

To enable others skilled in the art to understand the construction and operation of my invention, I will proceed to describe it with reference to the drawings.

A is the body or cylinder of the pump, the internal parts of which may be of any ordinary construction. B is the hollow piston-rod, the upper end of which projects upward through a suitable stuffing-box into a fixed pipe, C, the use of which is to receive and conduct upward the water from the hollow piston-rod, and thus obviate the necessity of extending the said rod the entire height to which it is desired to elevate the water or other fluid.

D is the frame that supports the working parts of the apparatus, and is furnished with a short upright standard, a, in the upper end of which is pivoted the operating-lever E.

r is a collar, the sides of which are flat, and which is firmly secured to the piston-rod B by means of a set-screw, n. The lower or short arm, f, of the lever E is bent at an angle

to the upper or long arm of the same, and is forked or divided into two branches, b, at its outer end each branch b extending past one of the flat sides of the block r; or, in other words, the forked end of the short arm f is made to embrace the collar r. Each branch b is furnished with a longitudinal slot, m, which may be curved somewhat, if desired, as represented in Fig. 1.

Close to the outer side of each branch b is a vertical standard, I, which is provided with a vertical slot, h, somewhat greater in length than the stroke of the piston-rod B and exactly in line therewith.

At each side of the piston B is a pin, d, which passes through the slot h of the standards I, and also through the slots m in the arms b, and is screwed into the block r. By this means the forked short arm of the lever E is connected with the piston B and the guiding-standards I.

A friction-roller, i, is placed upon each pin d where it passes through the slot h of the said standard. By moving the lever E to and fro a reciprocating motion is communicated to the piston B, the slots h, with which it is connected by the pins d, and their friction-rollers i, supporting it against any side pressure exerted by the operating-lever, and thus causing it to move uniformly in a straight or perpendicular line, while the slots m in the forked arm of the lever E allow the said lever to turn upon its pivot and the short arm f to describe the proper arc in operating the piston-rod, as just set forth.

What I claim as new, and desire to secure by Letters Patent, is—

The forked and slotted arm f of the lever E and the slotted vertical guiding-standards I, applied in combination with each other and with the collar r, pins d, and friction-rollers i, substantially as herein set forth.

I. VAN OLINDA.
